ABSTRACT: The specification discloses a security enclosure having a cylindrical wall with a base member permanently attached to close one end of the cylinder. A removable second closure member with two tabs is fitted within the other end of the cylinder with one tab extending through the opening of the wall of the cylinder and the other tab aligned with a matching lug formed by the wall of the cylinder. The tab and lug are secured together by means of a lock, padlock or other secure means.

SECURITY ENCLOSURE

SUMMARY OF THE INVENTION

The present invention discloses a new and useful improvement in the design of strong boxes and security enclosures. It provides a simple, inexpensive and easy to manufacture container having a minimum of parts and providing a maximum degree of protection.

Such strong boxes or security enclosures in the past have often required expensive machine operations in order to conceal their hinges and the seam around the opening to prevent the entry of pry bars and other destructive items. The present invention discloses a simple and inexpensive strong box that may be formulated from tube steel and sheet steel in a manner of minutes without any expensive hinges or other fittings and providing a relatively concealed hinge, clasp, and closure seam.

DETAILED DESCRIPTION OF THE DRAWINGS

FIG. 1 is a vertical elevation view of my new and improved security enclosure.

FIG. 2 is a top or plan view of an alternate form of my security enclosure.

FIG. 3 is an isometric view of my security enclosure.

FIG. 4 is an isometric view of an alternate form of the security enclosure with locking means.

Referring to the drawings in detail, like characters of reference denote corresponding parts throughout the several views.

As previously stated, the security enclosure is especially designed to provide an inexpensive, simple and secure strong box. In the preferred form of the invention, a cylindrical member 11 is permanently closed on one end by closure member 12. This closure may be effected by welding, riveting or by forming the container 11 in a mold and forming an integral one piece bottom closure member along with the sidewall 11. In the preferred form of the invention a steel plate 12 is welded to a steel tube 11 along the welds 13 to provide a permanent and virtually indestructible joint.

The other end of the cylindrical closure 11 is closed by closure member 14.

Referring to FIG. 3 closure member 14 is a circular disk of steel, iron or other relatively impenetrable material and in the preferred form of my invention is formed with the first and second tab member 15 and 15a. Tab member 15 extends through an opening 16 that is defined in the wall of the container 11. This opening is better illustrated in FIGS. 1 and 2, said opening being defined as an elongate slot to receive closure tab 15. On the opposed wall of the container 11, lug 17 is axially aligned with the second tab means formed on closure 14. Tab member 17 may be welded or bolted onto the wall of container 11, or otherwise secured thereon.

As illustrated in FIG. 4, lug member 17 is formed by two vertical cuts 18 and 19 that are made in the wall of cylinder 11. The material lying between the cuts 18 and 19 is then bent outwardly to a horizontal position to form an integral one piece tab having the same strength as the wall of the container. Tab 17 may be bent inwardly or outwardly depending upon the type of locking means employed. In the preferred embodiment, a pad lock or combination lock 20 is fastened through openings 21 and 22 by tab 15a and lug 17.

If a unitary locking means were used, tab 17 could be bent inwardly, and the locking means mounted internally as illustrated in FIG. 2. The locking means 23 would then be mounted on the closure 14 immediately inboard of container wall 11. Closure member 14 may be formed with an opening with an elongate slot opening 24 as illustrated in FIGS. 2 and 3 or without the elongate slot opening as noted in FIG. 4. Opening 24 is for the reception of dollar bills, change, or other valuable items such as inventory lists, store receipts, cash register tapes or other items which are normally secured for safe keeping.

It should be noted as illustrated in FIG. 3 that the seam 25 between the closure 14 and container 11 is recessed below the top of the container to provide a relatively inaccessible opening for pry bars or other instruments of destruction. This seam 5 may be further recessed without affecting the operation of the security enclosure by lowering slot 16 and tab 17 and leaving a larger lip than is illustrated in the preferred embodiment. If an outside cap were utilized or if the cap were even with the top of the container 11, it would be relatively simple and easy to 10 insert a pry bar and remove the enclosure member 14 by force. When the closure member 14 is recessed as illustrated in FIG. 3, the pry bar must be forced in to deform the wall of the container 11 before closure member 14 can be pried out. This gives the seam 25 an effective strength equal to the walls 15 of the container 11. The same is true at the slot opening 16. As illustrated at 26, the strength of the hinge is regulated by the thickness of the tab 15 as illustrated at 26, and a thickness of wall 11 as illustrated at 27. This gives the hinge member the 20 full strength equivalent of wall 11, and the closure member 14. Likewise, when tab 17 is formed integrally from wall 11, it and tab 16 which is formed integrally from disk 14, acquire the strength of the main wall members.

It should be noted that there are no such latch or hasp joints, seams or other weak areas that may be attacked, the tab and lug being formed integrally from the container and enclosure.

Referring to FIG. 4, the container may be equipped with a square member 29 as illustrated in FIG. 4 to provide a secure 30 and stable base for the security closure. In the event the enclosure is knocked over, base member 29 will prevent the container from rolling or otherwise moving about. This, base member 29 provides a stable base for the container in its horizontal or vertical position. If desired, openings 30 may be 35 formed in the base member 29 to secure the security enclosure to a wall, floor, or other stable building structure.

In the preferred embodiment of the invention, the container 11 has been disclosed and described as a cylindrical member, as cylindrical members generally present more wall strength 40 per volume than square members. Also, it is generally inexpensive and easy operation to fabricate the preferred embodiment of the invention from sheet steel and tube steel. If desired, however, container 11 could be formulated from sheet steel wherein the container 11 itself would be rectangle, square or other polygon and closure disk 14 would then assume a corresponding rectangular, square or polygonal shape.

While the preferred embodiment of the invention is described as being tube or sheet steel, it is obvious to one skilled in the art that the same could be formed of any type of 50 iron, including a cast iron wherein the lower closure 12 could be integrally cast with container 11. Also, it would be possible to form container 11 from a high impact plastic such as polystyrene of fiberglass reinforced resins to form a relatively 55 secure enclosure of a lightweight and portable nature. With those materials, it would also be possible to formulate closure 12 or 29 as an integral part of container 11 to simplify the assembly and construction of my invention.

While I have shown and described the preferred construction and arrangement of the various parts, it will be understood that the device is amenable to considerable modification without departing from the essential features, or sacrificing any of the advantages of the invention.

I claim:

65 1. A security enclosure comprising an openmouthed container having at least one enclosing wall and a base member, said enclosing wall defining an opening therein adjacent to the open mouth of said container, and defining an integral lug means formed from said wall adjacent to said open mouth, 70 said lug extending outwardly from said exterior wall at a 90° angle, said wall defining an opening above said lug extending from said lug to the open mouth of said container, a removable closure with first and second tab means for completely closing said open mouth, said closure normally mounted 75 within said closing wall and below the open mouth of said con-

tainer, said second tab means being axially aligned with said lug means mounted on said container wall when said first tab means extends through the opening defined in said enclosing wall, said lug means mounted on said wall opposed to the opening defined in said enclosing wall, each being on the outer extremities of said wall, said first and second tab means mounted on said removable closure opposed to each other on the outer perimeter of said removable closure, said tab means

and said lug means adapted to receive a locking means to secure the closure member to said container, said base member being formed of a polygonal sheet member and completely and permanently enclosing one end of said cylindrical container, said base extending outwardly beyond said enclosing wall to provide a stable base when said container is oriented in either a vertical or horizontal position.

UNITED STATES PATENT OFFICE
CERTIFICATE OF CORRECTION

Patent No. 3,610,177 Dated October 5, 1971

Inventor(s) Leroy H. Shapiro

It is certified that error appears in the above-identified patent and that said Letters Patent are hereby corrected as shown below:

Column 1, 12th line from the bottom, after "22" insert -- defined --; the penultimate line, delete "or" and insert therefor -- and --. Column 2, line 19, delete "closure" and insert therefor -- enclosure --; line 23, delete "such"; line 24, after "joints," insert -- screws, --; line 31, delete "This," and insert therefor -- Thus, --; line 39, after "is" insert -- a --; line 43, after "be" insert -- a --; line 45, delete "of" and insert therefor -- or --; 8th line from the bottom, delete "if" and insert therefor -- of --; last line, delete "closing" and insert therefor -- enclosing --. Column 4, line 4, delete "cylin-"; line 5, delete "drical".

Signed and sealed this 18th day of April 1972.
